UNITED STATES PATENT OFFICE.

ABRAM B. HERR, OF LANCASTER, PENNSYLVANIA, ASSIGNOR OF ONE-THIRD TO ELAM M. ROYER AND ONE-THIRD TO JOHN H. MOSEMAN, BOTH OF LANCASTER, PENNSYLVANIA.

BRUSH MECHANISM FOR CAN-WASHING MACHINES.

1,275,025.

Specification of Letters Patent.

Patented Aug. 6, 1918.

Application filed August 4, 1915. Serial No. 43,540.

To all whom it may concern:

Be it known that I, ABRAM B. HERR, a citizen of the United States, residing at Lancaster, in the county of Lancaster and State 5 of Pennsylvania, have invented certain new and useful Improvements in Brush Mechanism for Can-Washing Machines, of which the following is a specification, reference being had therein to the accompanying 10 drawing.

This invention relates to a brush mechanism for use in milk can washing machines, and more particularly to the machine described and claimed in my United States 15 patent application, Serial No. 43539, filed Aug. 4, 1915.

The object of the present invention is to provide brush holding and operating mechanism, which shall be automatic in its action, 20 retain the brushes in a detachable manner, and so operate them as to reach all parts of the can.

With these and other objects in view, my invention consists in certain constructions 25 and combination of parts as will hereinafter be fully described and claimed in the specification, and illustrated in the accompanying drawings which form a part of this application, and in which like figures of reference 30 refer to corresponding parts in all of the views; but it is fully understood that while I have here described my device as shown, I do not confine myself to the exact design, as slight changes may be made in the construction and arrangement of the several 35 parts without departing from the spirit of the invention.

In the drawings:—

Figure 1, is a front elevation of the device 40 showing the same in an operating position, and a can in place shown in section.

Fig. 2, is a similar view of the same in a closed position ready to enter the can.

Fig. 3, is a side elevation of Fig. 2, with 45 the brushes removed.

Fig. 4, is an enlarged sectional detail view of a portion of the operating means.

Figs. 5 and 6 are vertical sections, the section in Fig. 6 being taken at an angle to 50 that shown in Fig. 5.

Referring to the drawings 1, is the vertical combined water and steam pipe which is open at the upper end to supply steam and water to the brushes, while within the can,

and which is connected at the bottom by the 55 coupling to the piping system of the machine.

Mounted on the pipe 1, is a tubular shaft 2, which has a vertical sliding adjustment, which will hereinafter be fully described. 60

Embracing the shaft 2, is a second hollow shaft 3, which is rotated by a bevel gear 4, secured thereon, near the lower end thereof, and adjacent to the frame 5, of the machine and operated by a bevel gear 6, on a horizontal drive shaft 7, mounted in the frame 5, of the machine.

Mounted upon the lower end of the shaft 2, and secured thereto by the pins 8, is a flanged sleeve 9, upon which is a cushion 70 spring 10, having the washers 11, above and below and limiting the action of said spring 10; while mounted on the vertical rods 12, in the frame 5, is a yoke 13, embracing the sleeve 9, and being against the upper washer 75 11, and operated by a lever 23'. The operation of lever 23' causes the movement of yoke 13, and the sleeve 9 rigidly carried by shaft 2, and therefore controls the vertical movement of the shaft. 80

Above the frame 5, on the shaft 3, is a collar 14, for holding the grip tank 55 shown in Figs. 5 and 6.

Above this is mounted the lower set of brushes for washing the mouth of the can, 85 which comprises a spider 15, secured in a rigid manner by the pin 16, to the shaft 3, and a second spider 17, slidably mounted on the shaft 3, and prevented from revolving thereon by a feather 18, secured in said shaft 90 3, and engaging a keyway in said spider.

Hinged to said spider 17, are the lower ends of links 19, having their upper ends hinged to the brush holders 20, which have their upper ends hinged to the spider 15, 95 in such a manner that when the shaft 3, is revolved, the brushes will be thrown by centrifugal force into the position shown in Fig. 1.

The upper set of brushes for washing the 100 inside of the can 21, are mounted as follows:—

A collar 22, above the upper end of the shaft 3 is movable vertically, and a member 23, is slidably mounted on the shaft 3, in the 105 following manner, viz., referring to the detail shown in Fig. 4, this member 23, is provided with the screws 24, threaded through

the side thereof, and having their ends extending through slots 25, in the walls of the shaft 3, and into the holes 26, in the walls of the shaft 2.

5. By this construction the shafts 2, and 3, and the member 23, all revolve upon the pipe 1, and the member 23, and shaft 2, are locked together and yet vertically movable upon the shaft 3.

10. The upper end of the member 23, is provided with ears 27, within which are pivoted the lower ends of the brush block links 28, and 29. The link 28, is pivoted to the brush block 30, while the link 29, is pivoted to the 15 brush block 31, near the lower end thereof.

The collar 22, is also provided with similar ears 32, to which are pivoted one end of the links 33, and 34. The outer end of the link 33, is pivoted to one end of the brush block 20 35, and the outer end of the link 34, is pivoted to a short link 36, connecting with the upper end of the brush block 31.

Below the member 23, is a collar 37, which is slidably mounted on the shaft 3. Upon 25 the stud screw 38, are pivoted the lower ends of the adjustable arms 39; while to the upper ends of said arms 39, are pivoted the lower ends of a pair of cross arms 40, which are pivoted at their point of intersection 41, 30 to the collar 22, and their upper ends are connected by links 42.

There is also a link 43, connecting the pivot point of one link 42, and one arm 40, with the top of the brush block 30, and a 35 link 45, connecting the top of the brush block 30, with the bottom of the brush block 35.

The can is inverted and placed in the position shown in the drawings with the 40 brushes in collapsed position therein. In starting the washing operation the yoke 13 is moved to its upper position by means of a lever 23' raising shaft 2 and collar 23 to a limited extent, and rotary movement is imparted to shaft 2 by the driving means. The centrifugal force will expand the upper brushes and permit them to move upwardly, in view of the mounting means described. The lower set of brushes is opened by 45 centrifugal action, the spider 17 sliding on the shaft 3 against the action of spring 50.

When the bottom of the inverted can and the adjacent portions of the walls have been cleaned, the remaining portions of these 50 walls are then operated upon.

The initial downward movement of yoke 13 by lever 23' will pull shaft 2 downwardly and carry collar 23 downwardly and thereby move collar 37 downwardly and permit collar 22 to move down, in view of the link connection 39 with collar 37 and link connection 40 with collar 22, the brushes remaining in expanded position but being lowered.

On the further downward movement of 55 the yoke 13 the collar 22 engages the upper

end of the shaft 3 and collar 23 continues to move down and closes the brushes by means of the links 39 and 40.

Having thus described my invention what I claim as new, and desire to secure by Letters Patent is:—

1. In a device of the class described, a tubular shaft for conveying cleaning fluid, a slidable shaft mounted thereon, a rotatable shaft carried by the slidable shaft, a set 75 of collapsible brushes driven by the rotatable shaft and positioned to engage the neck portion of a can, a spring retaining said brushes normally in collapsed position, a collar slidable on the rotatable shaft, a collar slidable on the shaft first named, an additional collar slidable on the rotatable shaft and movable therewith, a second series 80 of brushes and link connections between said brushes and the first and second named collars, and link connections between the link connections first named and the additional collar for collapsing the brushes.

2. In a device of the class described, a tubular shaft for conveying cleaning fluid, a 90 slidable shaft mounted thereon, a rotatable shaft carried by the slidable shaft, a set of collapsible brushes driven by the rotatable shaft and positioned to engage the neck portion of a can, means for retaining said 95 brushes in collapsed position and permitting the brushes to be thrown outwardly by centrifugal action, and a set of brushes above the brushes first named for engaging the inner walls of the can, and means for 100 mounting the brushes last named and giving an initial upward movement thereto by the movement of the slidable shaft, said mounting means permitting of the expansion of the brushes last named by centrifugal action.

3. In a device of the class described, a tubular shaft for conveying cleaning fluid, a 110 slidable shaft mounted thereon, a rotatable shaft carried by the slidable shaft, a collar slidable on the rotatable shaft, a collar slid- 115 able on the shaft first named, an additional collar slidable on the rotatable shaft and movable therewith, a series of brushes and link connections between said brushes and the first and second named collars, and link connections between the link connections first named and additional collar, for collapsing the brushes.

4. In a device of the class described, a 120 tubular shaft for conveying cleaning fluid, a plurality of concentric shafts carried by the shaft first named, one of said concentric shafts being slidable and the other of said shafts being rotatable, driving means for 125 the rotatable shaft, a set of brushes and mounting means therefor, means for driving the brushes by the rotatable shaft, and means for throwing them upwardly by the longitudinal movement of the slidable shaft, 130

said brushes being thrown outwardly by centrifugal action and moved upward by the mechanical action of the mounting means incident to the centrifugal action.

5. In a device of the class described, a plurality of concentric shafts one of which conveys a cleaning fluid, one of which is slideable longitudinally and one of which is rotatable, means for driving the rotatable shaft, a set of brushes including a plurality of oppositely located brush elements, and an additional brush element mounted above those first named, said rotatable shaft imparting rotary movement to all of the

brushes and the mounting means permitting them to be thrown outwardly by centrifugal action, and the slideable means effecting the vertical movement of the brushes, said additional brush being mounted to assume a position at an angle with the brushes first named.

In testimony whereof I affix my signature in presence of two witnesses.
